PRINTING DEVICE

Edward J. Rabenda, Binghamton, N. Y., assignor
to International Business Machines Corpora-
tion, New York, N. Y., a corporation of New
York

Original application May 16, 1934, Serial No.
725,837. Divided and this application January
10, 1935, Serial No. 1,087

10 Claims. (Cl. 101—93)

This case is a division of my copending applica-
tion Serial No. 725,837, filed May 16, 1934.

The present invention relates to improvements
in fraction printing devices and more particu-
5 larly is concerned with perforated record card
controlled apparatus which is adapted to receive
entries of debit and credit amounts in English cur-
rency and to list a printed record thereof.

An object of the invention is to provide an im-
10 proved means for printing debit and credit
amounts in the duo-decimal system, such as
pence, twelfths, inches, dozens, etc.

A feature of the invention is the improved de-
vices for using a standard Hollerith type of record
15 card for controlling the printing of positive or
negative fractions and English currency amounts.

Another object of the invention is to provide
means for controlling the printing of a multi-
20 denominational ordered number by means of a
special perforation on a record card.

An object of the invention is to provide means
for sensing a special perforation representing a
25 multi-denominational ordered number on one
cycle of the machine, and then causing printing
of such a number on the following cycle of the
machine.

An object of the invention is the provision of
devices for entering and printing complements of
a multi-denominational number represented by a
30 single perforation on a record.

Another object of the invention is the provision
of printing control devices adapted for universal
use in the decimal system, for fractional repre-
sentation and English currency tabulation.

35 A feature of the invention is the selective con-
trol of two typebars by a single column of perfora-
tion positions on a card or a single position on
an accumulator wheel. The printing of a single
40 decimal digit by one bar or the printing of duo-
decimal figures by two bars represents either an
entered item or a total.

Further objects, uses, and advantages of the
present invention are pointed out hereinafter in
45 the specification and claims and shown in the
drawings which illustrate what is considered to
be the preferred embodiment of the invention.

In the drawings:

Fig. 1 is a side elevational view of the machine
showing the driving and operating connections.
50 Fig. 2 is a vertical section taken through the
center of the machine.

Fig. 3 is a detail view of a portion of the perfo-
rated record card used to control the machine.

Fig. 4 is a portion of a record strip showing the
55 recording of a few amounts and a total.

Figs. 5A and 5B, when taken together, form a
wiring diagram of the machine.

Referring to the portion of the card 1 disclosed
in Fig. 3, a plurality of columns of index point
positions ranging from R to 9 are shown. An
amount which is to be added or subtracted in a
5 machine is entered by perforations in the suc-
cessive columns. The card shown is perforated to
represent two amounts in English money. The
one amount is 6 pounds and 10 pence; the other
amount is 13 shillings and 11 pence. The index
points designated X are used to signify ten pence
in a units order and the index points marked R
are used to position a perforation for the repre-
sentation of 11. The X index point positions in
10 certain orders have another controlling value
when perforated. Thus, on the card shown the
perforation "2" shows that the amounts on the
record are credit items. The amounts are punched
in the same manner to indicate either a credit
15 item or a debit item. If the card contains a
credit item, the control perforation "2" is punched
in the upper portion of the card and used to
control the machine to effect reverse operation
of adding and subtracting in the accumulators
20 of the machine. In the absence of such a perfora-
tion, the machine will effect addition of a true
number in a debit accumulator and add the com-
plement of the true number in the credit accu-
mulator.

In Fig. 3, the perforation "2" is shown in the
twelfth column of index points on the card. The
perforation may be placed in any of the columns
and the machine may be plugged accordingly.

The cards are fed through the machine by feed
rollers and analyzed successively by upper sensing
35 brushes UB and lower sensing brushes LB in the
usual way. The card is fed past the brushes with
the 9 index point position passing under the
brushes first, followed by the 8 position, and then
40 the 7, and so on in a manner which is well known
in the art.

The upper brushes are used for control sensing
while the lower brushes effect the adding and sub-
tracting of the amounts represented on the card.
When an item on the card is to be added in one
45 of the accumulators and a perforation appears in
the first column in the 6 index position (as in Fig.
3) then when the perforation passes under the
lower brush the related accumulator wheel is
50 clutched to the driving means to commence adding
one unit as each of the succeeding points on the
card passes under the brush. At the time the zero
position passes under the brush, the machine
55 automatically declutches the accumulator wheel.

so that it stops turning. It will thus have turned six steps to accumulate the value 6. In the fourth column on the card, the related lower brush will contact with the perforation in the X position to 5 clutch the related accumulator wheel to commence adding one step before the nine position on the following cycle of the reading in the card. Then, when the zero position is reached and the wheel is declutched, the value 10 will have been 10 added.

During the entry of a credit item, the described adding operation takes place in the credit accumulator. The machine may be arranged so that as this is occurring, a debit accumulator may be controlled so as to enter the complement of the number added in the credit accumulator. In order that an accumulator may receive the complementary amount, its accumulator wheels are clutched early in the cycle so as to commence adding in 20 all orders except the units order when the 9 index point position on the card passes under the lower brushes. The units order or pence wheel is clutched three steps before the other wheels. When a perforation is sensed by the lower brush in any 25 particular column, the accumulator wheel in the credit accumulator is declutched. Another form of mechanism is provided to take care of the entry of complements in the pence orders. This mechanism is operated to enter the value 1 or 2 30 according to whether 11 or 10 pence perforations are presented in the pence order columns of index points.

In the order representing tens of shillings or 35 half pounds the clutching of the accumulator wheel takes place in the index point 1 and is adapted to cause the entry of either one or zero according to whether the index points zero or one are punched in the card. In this way the complement of any possible number of shillings ranging 40 up to 19 may be entered in the tens and hundreds wheel representing units and tens of shillings.

When a perforation is sensed by the lower 45 brushes in any of the columns other than the pence or shillings columns, the related accumulator wheel in the debit accumulator is declutched. Thus, with the card of Fig. 3, the debit accumulator wheel associated with the first column will commence adding as the nine position passes the 50 related lower brush and then as the 6 position passes the brush the perforation in this position will be sensed and the energization of an electromagnet will cause the accumulator wheel to be disengaged after entering the amount "3" which is the complement of the figure 6 represented on the card. Since no perforations appear in the 55 next two columns on the card, the complement 19 will be entered into these two accumulator wheels. The fourth column is perforated to represent the 60 value 10 and therefore the amount 2 is entered into this order since the values 2 and 10 are complementary in the duo-decimal system.

Printing mechanism

65 The printing mechanism includes a platen 92 (Fig. 2) and a series of type carriers 93 each having a plurality of type elements 94 adapted to be struck by a hammer 95 loosely pivoted on a shaft 96. The type carrier is connected at its lower end to an arm 97 fulcrumed at 98. Springs 99 connected to the arms 97 and to a cross beam 100 connected between arms 101 pivoted at 102, tend to raise the arms 97 to raise the type carriers.

70 A restoring ball 103 connected by links 104 to

arms 101 is adapted to restore the arms 97 to their lowest or normal position.

An arm 105 (Fig. 1) fixed to the shaft 102 on which the arms 101 are also fixed, is connected by a link 106 to a complementary cam follower arm 107 pivoted at 108 and cooperating with cams 109 and 110 on cam shaft 111.

5 Shaft 111 is driven through a chain of gears 112, 113, and 114 the latter of which is mounted on shaft 23'. The shaft 23' turns in synchronism with the feeding of the cards through the machine, and thus the ball 103 (Fig. 2) is raised so as to permit the type carriers to rise in synchronism with the feeding of the card.

10 Thus when the type element 94 carrying the numeral nine is approaching the printing line with respect to platen 92 and the actuating hammer 95, the nine position on the card will be passing the card reading brushes LB. If there is a perforation in the card at the nine position, a circuit will be closed through the brush LB to a printing magnet PM (Fig. 2) of that particular column. This will attract the associated armature 115 which is connected to one of the rods 116 which at the other end is connected to a latching member 117 of that particular column. This will release a latching pawl 118 permitting it to operate with the top one of the ratchet teeth 119 carried by the type carrier to stop the type carrier with the nine type 94 in line for printing.

15 When the arms 101 raise the ball 103 to permit the type carriers to rise, the springs 99 will be stretched when the type carriers are latched and the arms 97 are stopped in differential positions. After printing has been effected, the arms 101 are 20 then lowered with the ball 103 to restore the type carriers to normal position.

25 The latching pawls 118 must then be restored before the type bars can begin the next upward movement. For this purpose a ball 120 is adapted, when rocked clockwise, to rock the latching pawls 118 counterclockwise against the action of their spring and permit them to be latched by the latches 117. The ball 120 is connected by a link 121 to arm 122 fixed on shaft 123 on which is also 30 fixed an arm 124 (Fig. 1) connected by link 125 to an arm 126 pivoted at 127 and connected to a cam follower arm 128 (Fig. 2) adapted to be actuated by a cam 129 on shaft 111.

35 The several type actuating hammers 95 are actuated by individual springs 130 tending to rock them against the type 94 to effect printing. The hammers are normally locked in their retracted position by individual latches 131. These latches are connected to levers 132 adapted to be moved to the left by a bar 133.

40 The bar or bail 133 is pivoted at 134 and is connected to an arm 135 (Fig. 1) connected by a link 136 to a bell crank 137 in turn connected by a link 138 to an arm 139 fastened to a shaft 140 which carries (see Fig. 2) a cam follower arm 141 having rollers 142 cooperating with complementary cams 143 mounted on shaft 111.

45 A ball 144 which restores the hammers to normal position is supported on a pair of arms fixed on the shaft 96 to the end of which is fixed the crank 137 (Fig. 1). The pin and slot connection 145 between link 136 and arm 135 permits the shaft 96 to turn clockwise a slight amount without link 138 moving arm 135. This is arranged in order that ball 144 (Fig. 2) may be moved out of the path of the hammers 95 before the arm 135 and ball 133 are actuated by link 136 to release the hammers.

Where listing is to be effected on a record sheet 146 (Fig. 4), while an item is also being accumulated, the printing magnet PM will be connected to receive an impulse through the perforation in the card simultaneously with the transmission of such impulse to the related accumulator magnet AP, A or AH. The amount may be listed whether the item is a debit or a credit.

10 The total taking control

When a total is to be taken of a group of items which have been accumulated, and the total or balance is to be printed, it is necessary to open the listing circuits to the sensing brushes and close the total printing circuits to contacts in the accumulator. The mechanism for effecting these circuit changes is controlled by a total control magnet TM, the operation of which is explained with reference to the wiring diagram. This magnet is adapted to be energized either by depression of the total key or automatic operation of group control devices whenever a total is to be taken.

25 The plugboard circuit breaker switch

During accumulating, total taking and transferring operations it is necessary to break connections between the sensing brushes, the accumulator magnets and the total printing contacts in order to prevent back circuits.

The devices for opening and closing the contacts PBCA and PBCB (Fig. 5B) are shown in Fig. 2. A plate 185 is fastened to the machine frame near the card feed control shaft 154. The plate carries a series of contacts arranged in groups of three, an upper blade 186, a center blade 187, and a lower blade 188. Each center blade 187 projects into a slot 189 cut in the side of a vertical insulation bar 190 riveted on a link 191.

40 A bell crank 192 pivoted at 193 is pivotally connected to the link 191 at 194, and on the end of a vertical arm carries a roller 195 cooperating with a cam 196 on shaft 154. Another horizontal arm (not shown) guides the lower end of link 191. The cam 196 has three different concentric levels 197, 198 and 199 for adjusting crank 192 and controlling the contacts.

Early in the counterclockwise movement of cam 196, the roller is raised to level 197 and the crank is rocked counterclockwise to close the upper contacts PBCA and condition the machine for adding so that the impulses from the lower brushes are directed to the accumulator magnets. At transferring time, the crank roller 195 falls to level 198 and closes the lower contacts PBCB enabling the transmission of transferring impulses through the transfer contacts to the accumulator magnets. Then finally the crank is brought to rest on level 199 whereupon both contacts PBCA and PBCB are opened and the machine is adapted to take a total.

The machine operating connections

The wiring diagram in Figs. 5A and 5B shows the control connections in the machine for effecting adding, subtracting, transferring, printing and total taking.

70 The source of energy is at PS (Fig. 5A) and includes the lines 200 and 201. When the switch is closed at PS, the operating motor M is energized and turns the shafting to which may be clutched the various mechanisms in the machine. Another main line 202 is connected to line 201 through contacts CR4, CR5, CR6, and CR7 which are closed instantaneously as the index point positions

on the card appear under the upper and lower brushes UB and LB.

When the start key is depressed, contacts 203 are closed and a circuit is established from line 200, through the stop key contacts 216, contacts 5 MI1, card feed clutch magnet CFCM, magnet R6 in parallel therewith, contacts 203 and wire 204 to line 201.

The energization of magnet CFCM will cause 10 operation of the card feeding mechanism to feed cards through the machine. This magnet also controls contacts CFC1 and CFC2, closing them when the magnet is energized. As the cards feed through the machine they depress the lower card lever and operate the lower card lever contacts 15 LCL. The magnet R6 closes contacts R6B as long as cards are feeding, but opens these contacts to prevent the passage of pence accumulating and printing impulses during the taking of a total.

When contacts LCL are closed a circuit is established through magnets CLR and CLRH, from line 200, through contacts LCL, magnets CLR, CLRH, in parallel, and wire 205 to line 201. The magnet CLRH when energized forms a holding 25 circuit by closing contacts CL1 which are in series with contacts CR2 which close when contacts LCL open. The other magnet CLR closes contacts CL4 in parallel with start key contacts 203, so that by means of contacts CFC1 and CL4 the 30 energization of magnet CFCM is maintained after the start key is released. If the auto start switch AS is closed as shown, the closing of the contacts P1 at the end of a total cycle serves to energize the magnet CFCM and resume card feeding. If 35 cards fail to feed because of an empty magazine or jammed cards, the contacts LCL remain open and the circuit is opened at CL4, deenergizing the card feed clutch magnet and stopping the card feeding mechanism.

If printing is to be effected under control of the cards being fed through the machine, the list switch is closed as shown so that when contacts CFC2 are closed by magnet CFCM and contacts CL3 are closed by magnet CLR, the printing clutch 45 magnet PCM is energized. The circuit is as follows: line 200, wire 206, magnet PCM, wire 207, contacts PC1, contacts CFC2, contacts MI5, the switch arm, contacts CL3, and wire 208 to line 201.

The energization of magnet PCM causes the 50 printing operation devices to be clutched to the main operating mechanism so that the type bars and associated mechanism are operated. If tabulating control of printing is desired, the switch may be shifted to TAB, then during the 55 printing of the first card after a total, contacts P2 open to deenergize magnet PCM. The magnet remains deenergized during the accumulation of a group of cards because contacts PC1 are opened by the unlatching of armature 209 by energization of magnet PCRM. The circuit includes line 200, contacts CL2 closed by magnet CLRH, contacts CF2, contacts P3 closed during the printing 60 of the first card after the total, magnet PCRM, the switch arm at TAB, contacts CL3 and wire 208 to line 201.

The magnet PCM may be energized for the 65 printing of a total by the automatic closing of contacts MI2, or the closing of contacts 211 by the hand total key. The circuit is from line 200, wire 206, magnet PCM, wire 212, contacts MI2, wire 213, the switch HTS in the position shown for automatic totals or moved to the left 70 for hand totals, thence through wire 215 on con- 75

tacts 211, contacts CR3 normally closed, and wire 320 to line 201.

While the machine is in operation and cards are being fed the machine may be stopped at any time by depression of the stop key to open the contacts 216. This will break the circuit through the card feed clutch magnet CFCM which then allows contacts CFC2 to open to deenergize the printing clutch magnet PCM. The operating 10 motor will continue to operate until the switch at PS is opened.

A platen feed mechanism is provided to feed the record paper before printing in both listing and total taking operations. A platen feed magnet PFM, when energized acts to clutch the platen spacer to the driving mechanism. The circuit through the platen feed magnet is as follows: line 200, wire 210, switch SF, contacts CF11, contacts P4 closed during printing, paper feed magnet 15 PFM, and wire 214 to the other line 201. The magnet may be energized in automatic total taking by the closing of contacts MI3 and contacts P5.

The passage of cards under the upper brushes 25 UB serves to deenergize magnets R1 and R2 which in turn control the operation of many contacts throughout the machine. These contacts are associated with magnet R2 and are operated thereby to indicate the presence of cards under 30 brushes UB. When cards fail to appear under the brushes UB a circuit is closed through line 202, wire 218, common brush 230, contact roller 231, brush 279, contacts CF9, magnets R1 and R2 in parallel and wire 280 to line 200. Magnet R1 35 closes associated contacts R1A and a holding circuit is established through contacts CF8 and R1A.

In an ordinary adding operation, as the card passes the lower brushes LB the amount perforated therein is added and printed. The circuit 40 is from line 200 (Fig. 5A), contacts CL2, wire 246, contacts CF2, common brush 219, contact roller 220, brush LB touching roller 220 at a differential time controlled by the location of the perforation, jack 221, plug wires to jacks 224 and 261 45 if both adding and listing control is desired; then the circuit branches out in two parallel circuits, the printing or listing branch includes contacts 174, printing magnet PM and line 202; the adding branch continues through jack 224, cable 50 225, (Fig. 5B), contacts 47B closed for adding, wire 350, contacts PBCA closed during accumulating, wires 351 and 352, contacts 174 closed for item entry, accumulator magnet A and line 202.

The energization of the accumulator magnet 55 acts to clutch the accumulator wheel to the driving gear and rotation continues until cam 51 (Fig. 7) declutches the gears.

The addition of the amounts 1 to 9 are carried out in a similar way in the pence order. The 60 circuit for the addition of such numbers in this lower order bank may be traced at the top of Fig. 5B. The impulses from the lower brushes travel along the cable 225, through wire 353, contacts PBCA, wire 354, contacts 355, wire 356, 65 contacts 357, wire 358, contacts 359 closed during adding, wire 360, wire 352, contacts 174, magnet AP and line 202.

The listing of the ordinary decimal figures in the pence order follow a path somewhat different 70 from the printing circuit in the higher orders. The circuit may be followed in Fig. 5A from line 200, contacts CL2, wire 246, contacts CF2, common brush 219, contact roller 220, brush LB in the lower order, jack 221, a plug wire to socket 75 224, wire 361, contacts 362, plug socket 363, a

plug wire to socket 261, in the pence order of printing bank, contacts 174, magnet PM and line 202.

In the adding of ten or eleven pence in the lowest order of the accumulator a different mode of entry is employed. The perforations representing these two amounts are placed at the top of the column of index points on the record card 1. Referring to Fig. 3, it is noted for the perforation in the fourth column from the left 10 that the X position represents 10 pence. A perforation in the 9th column at the R index position represents 11 pence. These two perforations are sensed as the card passes through the upper brushes, one card cycle before the regular 15 adding operation takes place as the card passes through the lower brushes. The sensing of such perforations causes contacts to be adjusted for the early meshing of the accumulator wheels to add the amount 10 or 11.

Considering first the mode of operation for the entry of 10 pence, the sensing of an X perforation in the pence column sets up a control circuit which may be traced starting with line 202 (Fig. 5A) through wire 218, common brush 230, contact roller 231, brush UB in the lowest order, socket 232, a plug wire to socket 233, magnet R10, wire 364, brushes 365 which make contact with a segment 366 on a commutator 367 which is rotated in synchronism with the feeding of the card and adjusted to make contact as the X position passes the upper brushes. The circuit continues through brush 368 contacting a continuous ring on commutator, contacts CF5, contacts R2A and line 200. The energized magnet 35 R10 closes contacts R10A and sets up a holding circuit including magnet R156. The circuit may be followed from line 200, wire 369, contacts CF15, wire 370, contacts R10A, holding magnet R10H and magnet R156 and wire 371 to line 201. The energized magnet R156 holds contacts 367 opened and contacts 372 closed during the following cycle to add 10 pence into the accumulator.

The circuit through accumulator magnet AP for the addition of 10 pence may be followed from 45 line 202 (Fig. 5B) magnet AP, contacts 174, wire 352, wire 360, contacts 359, wire 358, contacts 372 operated by magnet R156, wire 373, brush 10A cooperating with a commutator 374 provided with a spot 375, contacting brush 10A, early in 50 the adding operation at the time calculated to mesh the accumulator wheel to add the value 10. The circuit continues through spot 375 to a contact ring 376, common brush CA, contacts R6B, wire 377 (Fig. 5A), wire 378, wire 246, and contacts CL2 to line 200.

During the adding of the 10 pence in the lowest order of the accumulator, the number ten is printed on the record sheet 146 (Fig. 4) as shown by the second item on the sample sheet. For 60 this purpose, two orders of the printing device and two type bars are associated with a pence order of the accumulator. When the magnet R10 is energized by the appearance of the X perforation, the contacts R10B (Fig. 5A) are 65 closed to effect the entry of an impulse at the one time in the operation of the machine to cause the tens of pence order of the type bars to print the figure 1. The listing circuit may be followed from line 202 (Fig. 5A) through the 70 pence order of the printing magnet PM, contacts 174, plug socket 261, plug wire to socket 379, contacts R10B, wire 380, contacts CF3 closed at the one index point, wire 381, wires 378 and 246, and contacts CL2 to line 200. In the lowest order 75

of the printing bank, the figure 0 will be printed since no perforation is sensed through contacts 362 during the rising movement of the lowest order type bar. Therefore, this type bar will 5 rise to the highest position with the 0 type in line with the printing hammer.

The entry of 11 pence into the accumulator involves an operation somewhat different from the entry of 10 pence. The existence of a perforation in the R position on the card is sensed as 10 the card passes the upper brushes. The circuit through the lowest order of upper brushes UB is similar up to the socket 233. There, the impulse is directed through magnet R11 through 15 wire 382 and brush 383 because the spot 384 on commutator 385 is timed to make contact as the R position is passing the upper brushes. The circuit continues through brush 386, contacts CF5, and contacts R2A to line 200.

20 The energized magnet R11 closes contacts R11A and sets up a holding circuit through holding magnets R11H and R157. The holding circuit includes line 200, wire 369, contacts CF15, wire 370, contacts R11A, magnets R11H and R157, wire 25 371 and line 201. Magnet R157 then closes contacts 387 (Fig. 5B) to connect the pence order magnet AP to a circuit timed to operate the accumulator gear for a movement of 11 steps. The circuit runs from line 202 (Fig. 5B) through 30 magnet AP, contacts 174, wire 352, wire 360, contacts 359, wire 358, contacts 357, wire 356, contacts 387, wire 388, brush 11A, commutator segment 389, contact ring 376, brush CA, contacts R6B, wire 377 (Fig. 5A), wire 378, wire 246 and 35 contacts CL2 to line 200.

At the same time that the value 11 is added in the pence bank, the two lowest order printing banks are operated to print the number 11. To do this, the magnet R157 opens contacts 362 (Fig. 40 5A), and closes contacts 390 at the same time magnet R11H closes contacts R11B. After these connections are made, the closing of contacts CF3 at the one index point directs a pair of impulses through plug sockets 363 and 379 energizing the two lowest order printing magnets PM 45 in time to print two figures one as shown in the fourth item on the same record in Fig. 4.

The appearance of a perforation at the X position on the card may not only indicate the 50 value of 11 pence, but its presence in certain columns, when the machine is plugged for control in subtraction, may indicate that the card carries a credit item which is to be subtracted 55 from other amounts such as debit items carried on cards free from such special perforations as perforation 2 in Fig. 3.

When the cards are fed through the machine they pass first under the upper brushes and then 60 one cycle later under the lower brushes. As the card passes under the upper brushes it is sensed to determine whether it carries a credit item accompanied with a special perforation such as the X hole 2. If such a perforation is sensed, 65 certain relays are energized to shift contacts so that the complement of the number on the card is added in the accumulator. If desired, true numbers of such credit amounts may be added at the same time that the complements are 70 entered into another accumulator then it is necessary that the accumulator orders be divided into two sections, one to receive the true numbers of credit items and complements of debit items and the other to receive two numbers of debit 75 items and complements of credit items. Such

construction is shown in the copending application of A. W. Mills, Serial No. 634,454, filed Sept. 23, 1932.

In the present case, the accumulator is shown as having only one accumulator designed to add and subtract English currency. It is understood that a pair of such accumulators may be provided to handle simultaneously debit and credit amounts.

The subtraction control circuit is as follows: 10 from line 202, wire 218, common brush 230, contact roller 231, an upper brush UB in a column plugged for sensing special perforations, plug socket 232, a plug wire to socket 391, magnet XC, contacts CF8, wire 321, contacts R2A and 15 line 200.

The energized magnet XC closes contacts 234 and sets up a holding circuit through magnets MC7 and to magnet XCH. This circuit is from 20 line 200, wire 369, contacts CF22, wire 392, contacts 234, magnets XC and MC7 and line 201.

The energized magnets MC7 operate a series of contacts 244, 245 to deenergize certain relays and energize other relays for the shifting of subtraction control contacts throughout the machine. Normally, the contacts 245 are closed to energize 25 relays R47, R49, R123 and R125 to control the direction of an adding impulse for the addition of a debit item. An example of a circuit through 30 one of such relays may be followed from line 200, through contacts CL2, wire 393, jack 394, plug wire to socket 247, contacts 245 normally closed, socket 248, plug wire to socket 395, magnet R47, bus bar 396, contacts CF26, and wire 371 35 to line 201. On the operation of magnet MC7, contacts 244 are closed and then the circuit is directed through plug socket 252 and a plug wire to socket 397, magnet R46, bus bar 396, contacts CF26, and wire 371 to line 201.

By reversing the plugging in certain orders, such as the highest order, in running a plug wire from 252 to 395 and from 248 to 397, a complement may be entered as other orders enter true numbers. For ordinary adding operation the 45 magnet R47 is energized by plugging directly from socket 394 to 395.

Considering first the entry of a complement in the ordinary accumulator banks other than the pence bank and half pounds bank. In these 50 orders, the accumulator magnet A is energized at the 9 index position to start the accumulator wheel revolving. The operation of accumulation continues until the associated magnet SC is energized by the appearance of the perforation at a 55 certain index point in a related column on the card. The differential position of the perforation determines the complemental value of the figure entered.

A circuit for the clutching of the accumulator wheels at the 9 index position may be traced 60 from line 200 (Fig. 5A), contacts CL2, wire 246, wire 378, wire 377 (Fig. 5B), contacts CF28 closed at the 9 index position, wire 398, wire 399, contacts R122A closed by magnet R122 during subtraction, contacts PBCA, wire 351, wire 352, contacts 174, through magnet A to line 202. This serves to start the accumulator wheel revolving and the operation of the wheel continues until a 65 perforation is sensed, then a circuit is directed through the related magnet SC (in the present instance the pounds order magnet) for the termination of the complement entry. A circuit may be followed from line 200, contacts CL2, wire 246, contacts CF2, common brush 219, contact roller 220, lower brush LB, socket 221, a 70 75

plug wire to socket 224, through cable 225 (Fig. 5B), contacts R123A closed for subtraction, wire 408, contacts 174, magnet SC and line 202.

The entry of a complement in the half pounds 5 or tens of shillings order follows a somewhat similar course of operation. However, in this order, it is unnecessary to add more than 1 as a complement at any time. The bank is designed to transfer when amounts larger than one are added in 10 it. Therefore, the related accumulator magnet AH is energized at the one index position for the meshing of the accumulator wheel to start the entry of a unit when a zero is presented in the related column on the card. The circuit through 15 magnet AH may be followed along a circuit from line 200, contacts CL2, wire 246, wire 318, wire 381, contacts CF3 closed at the one index position, wire 401 (Fig. 5B), contacts R122B, contacts PBCA, wire 351, wire 352, contacts 174, magnet AH to line 202. The circuit terminating the complement 20 entry operation is directed through a hole in a card to cable 225, contacts R123A, wire 500 and magnet SC associated with magnet AH in the same manner as described above in connection 25 with the termination of the complement entry in the pounds order.

For the entry of a complement in the pence order, the accumulator magnet is energized at a 30 time corresponding to a twelve index position, in other words, the magnet is energized three index 35 points before the regular nine index point position. This is done so that a complement of any number of pence from zero to eleven may be entered into the lowest order. The pence complement entry initiating circuit may be followed from line 200, contacts CL2, wire 246, wire 318, wire 377 (Fig. 5B), contacts R8B, contacts CA, contact ring 376 on commutator 374, a contact spot 402 located on the commutator in a position 40 to contact a brush 12A at the 12 index position.

The circuit continues through wire 403, contacts R124B, wire 351, wire 352, contacts 174 and magnet AP to line 202. The related accumulator wheel is meshed with the driving gears and rotation 45 is started and continued until magnet SC is energized. If SC is energized by any of the ordinary digit perforations 0 to 9, the complement terminating circuit follows a path which may be traced from the line 200, contacts CL2, wire 246, 50 contacts CF2, brush 219, contact roller 220, lowest order brush LB, socket 221, plug wire to socket 224, cable 225, wire 353, contacts PBCA, wire 354, contacts 355, contact wire 356, contacts 357, wire 358, contacts 404, wire 405, contacts 174, magnet 55 SC in the pence order, and line 202.

Should the values 10 or 11 be perforated in the pence column of index points, it is necessary to energize magnet SC early in the complement entering operation. This is done so that the value 60 2 which is the complement of 10 or the value 1 which is the complement of 11 may be added in the pence order. This early energization of SC is taken care of by the sensing of the X and R perforations under the upper brushes one cycle before the complement operation, just as in the adding operation they were sensed ahead of time and in the same way as in adding, the magnets R10 or R11 are energized according to whether a 10 or 11 perforation is sensed.

70 The control magnets R156 and R157 are operated selectively to close contacts 372 or 387 to make connection with commutator 374 in the same manner as in adding. The only difference being that in subtraction, the contacts 359 are 75 opened and the contacts 404 are closed so that

the special perforations are directed through pence magnet SC instead of magnet AP. In this way, the 10 and 11 impulses are adapted to pass through magnet SC to follow soon after the starting 12 impulse through magnet AP for the entry 5 of the complements 2 or 1 in the pence order.

The printing of amounts during subtraction of the values in the accumulator is similar in operation to the entry of printing impulses during addition. In the orders other than the pence order, the printing impulses follow the regular course from the lower brushes through socket 221 along a plug wire to socket 261 through contacts 174 and magnet PM. The true credit values perforated in the card are those represented on a record sheet. In the two printing banks associated with the pence order, control is again selectively effected through contacts 362 or contacts 380 or R10B or R11B. The printing impulses for the representation of the digits 0 to 9 are directed through contacts 362. The printing of 10 and 11 is controlled by the closure of contacts 380 and R10B and the closure of 380 and both R10B and of R11B, respectively.

The special perforation 2 (Fig. 3) has a further use under control of class selection or class elimination. In other words, the appearance of this perforation on the card may be used to control the machine to eliminate the addition or printing of the amounts represented thereon or to cause amounts in a plurality of fields on the card to be directed into a single set of printing banks or accumulator orders. For this purpose, the upper brush sensing the column allotted for the reception of the special perforation 2 is connected with a class selection magnet CS.

The circuit is as follows: from line 202, through wire 218, brush 238, contact roller 231, upper brush UB, socket 232, plug wire to socket 406, through magnet CS, contacts CF3, wire 321, contacts R2A and line 200.

The energized magnet CS closes an associated pair of contacts CSA and CSB to set up a holding circuit through magnet CSH and a set of associated magnets MCR. A circuit through magnets MCR includes wire 369, contacts CF15, wire 370, contacts CSB, magnets MCR and wire 371. The operated magnets MCR serve to shift class selection control contacts 299 and 300. These contacts may be connected between the lower brushes and the adding and printing magnets in many ways to direct the impulses controlled by the card.

The same contacts may also be used during the taking of totals to select the orders in the accumulator to be connected to the printing magnets for the control of the printing of the balance.

Since the basic novel features of the invention have been shown and described as applied to a single modification, it will be understood that various omissions and substitutions and changes in the form and details of the device illustrated and changes in its operation may be made by those skilled in the art without departing from the spirit of the invention. It is the intention, therefore, to be limited only as indicated by the scope of the following claims.

What is claimed is:

1. In a machine controlled by perforated records having columns of index points, means for sensing a perforation in a single column of index points, a plurality of typebars arranged together for printing the various denomination digits of a plural ordered number, means under control of said sensing means for controlling the adjustment 70 75 77

of said plurality of typebars, and means for impressing said adjusted typebars against a record sheet to print a plural ordered number.

2. In a machine controlled by records with regular digit perforations and special perforations, means for feeding said records, a typebar, means for moving said typebar in synchronism with the feeding of said records, means for stopping the typebar in any one of a plurality of differential 10 positions, a magnet controlling said stopping means, means under control of said digit perforations for energizing said magnet, contacts in series with said magnet, and means under control of a special perforation for opening said contacts 15 to prevent energization of said magnet and freeing the typebar to move to the last position in position to print 0.
3. In a machine controlled by records with regular digit perforations and a special perforation, 20 a typebar, means under control of the digit perforations in the record for positioning the typebar in corresponding digit printing positions, and means under control of said special perforation for positioning said typebar to print zero.
- 25 4. In a machine controlled by records with regular digit perforations and a special perforation, means for feeding said records, means for sensing said records, a typebar, means for moving said typebar in synchronism with the feeding of said 30 records, a magnet energized by said sensing means when a digit perforation is sensed, means under control of said magnet for stopping said typebar in any one of a plurality of digit representing positions, other means for energizing said magnet 35 at a time to stop said typebar in position to print 1, and means under control of said special perforation for releasing said magnet from control by said sensing means and adapting the magnet for control by said other means.
- 40 5. In a machine controlled by records with regular digit perforations and a special perforation, a typebar, means under control of any digit perforation for positioning said typebar in a corresponding digit printing position, and means under 45 control of said special perforation for positioning said typebar to print the digit 1.
6. In a machine controlled by records with regular digit perforations and two special perforations, a typebar, means under control of any digit 50 perforation for positioning said typebar in a corresponding digit printing position, and means under control of one of the two special perfora-

tions for positioning said typebar to print the digit 1, and means under control of the other of the two special perforations for positioning said typebar to print 0.

7. In a machine controlled by records with regular digit perforations and a special perforation, 5 a pair of type bars, one for the units order and one for the tens order, means under control of any regular digit perforation for positioning the units order typebar to print a corresponding 10 numeral, and means under control of said special perforation for positioning the units order typebar to print zero and the tens order typebar to print one.

8. In a machine controlled by records with regular digit perforations and a special perforation, 15 a pair of typebars, one of the units order and one for the tens order, means under control of any regular digit perforation for positioning the units order typebar to print a corresponding 20 digit, and means under control of said special perforation for positioning the units order typebar to print one and the tens order typebar to print one.

9. In a machine controlled by a perforated 25 record with regular digit index points and a special duodecimal index point, a printing bar, a magnet controlling the positioning of said bar in digit printing position, means for sensing said regular index points and controlling the energization of said magnet at a differential time to stop said bar in position to print a digit corresponding to the index point perforated, means for sensing said special perforation and controlling an early energization of said magnet to stop said bar 30 in position to print a duodecimal figure.

10. In a machine controlled by records with digit perforations and a plurality of special perforations, a sensing brush for sensing the special perforations, a plurality of magnets connected to said brush, commutator devices connected to said magnets for closing a circuit selectively through one of said magnets according to which special perforation is found in a record, a plurality of typebars, means for stopping said typebars in printing position, and means under control of the selected magnet for controlling said stopping means so that the typebars are positioned to print one of a plurality of multi-denominational 45 numbers.

EDWARD J. RABENDA. 50
